CLAIM

The ornamental design for a backpack blower, as shown and described.

DESCRIPTION

FIG. 1 is a front view of a backpack blower of the present invention.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view seen from top, front and right side thereof.

FIG. 8 is a perspective view seen from bottom, rear and left side thereof.

FIG. 9 is a cross-sectional view indicated by the arrows 9-9 of FIG. 1; and,

FIG. 10 is a view showing the backpack blower in use, wherein a nozzle is attached to the backpack blower.

The nozzle depicted by broken lines in FIG. 10 are showing portions of the article that forms no part of the claimed design.
